LINK CHAIN SUPPORT POST

Michael T. Russo, Bloomfield Hills, Mich.
(1805 Larchwood St., Troy, Mich. 48084)

Filed May 20, 1974, Ser. No. 471,404

Term of patent 14 years

Int. Cl. D25—99

U.S. Cl. D25—78

FIG. 1 is a front elevational view of a link chain support post showing my new design.

FIG. 2 is a side elevational view thereof, the opposite side being identical.

FIG. 3 is a cross-sectional view taken on line 3—3 of FIG. 1.

FIG. 4 is a rear perspective view thereof.

FIG. 5 is an enlarged top plan view thereof.

FIGS. 6—8 are enlarged cross-sectional views taken on lines 6—6, 7—7, 8—8, respectively, of FIG. 1.

FIG. 9 is an enlarged bottom plan view thereof.

FIG. 10 is an enlarged perspective view of the lower portion thereof.

I claim:

The ornamental design for a link chain support post, as shown and described.
